CLAIM

The ornamental design for the liquid medication dispensing nipple, as shown and described.

DESCRIPTION

FIG. 1 is a perspective view of the liquid medication dispensing nipple of the present invention illustrating the hinged lid in the open position thereof;

FIG. 2 is a perspective view of the liquid medication dispensing nipple of the present invention illustrating the device with the lid in the closed position thereof;

FIG. 3 is a side elevational view of the liquid medication dispensing nipple of the present invention illustrating the raised indicia volumetric gradation on the exterior surface of the nipple of the device thereof;

FIG. 4 is a side elevational view of the liquid medication dispensing nipple of the present invention illustrating the exterior surface of the nipple opposite of the raised indicia volumetric gradation thereof;

FIG. 5 is a side elevational view of the liquid medication dispensing nipple of the present invention with the hinged lid shown on the right hand side thereof;

FIG. 6 is a side elevational view of the liquid medication dispensing nipple of the present invention illustrating the hinged lid on the left hand side thereof;

FIG. 7 is a top plan view of the liquid medication dispensing nipple of the present invention illustrating the lid in the closed position thereof; and,

FIG. 8 is a bottom plan view of the liquid medication dispensing nipple.
